UNITED STATES PATENT OFFICE.

JOHN J. MANN AND WILLIAM J. MANN, OF OAKLAND, CALIFORNIA, AND MARSHALL H. VAN COEVERDEN, OF SAN MARCIAL, NEW MEXICO.

WAVE MOTOR.

Application filed July 9, 1925. Serial No. 42,415.

This invention relates to means, commonly known as "wave motors," which are employed for the purpose of transforming power generated by the waves of large bodies of water, particularly of the ocean, into usable form.

Heretofore many such structures have been devised, but none have met with continued success. Chief among the difficulties 10 has been the failure to develop a device which is sufficiently adaptable to the vagaries of the sea to yield good results and uniform development of power. Also the mechanical features themselves have failed to 15 give satisfaction, and in many cases this seems to have been due to too great complexity in structural design.

The objects of the present invention are to provide a simply designed device capable 20 of smooth and uniform operation under at least all normal conditions of the sea, with which power may be generated economically on a commercial scale. These objects include development of a structure which shall have 25 long life and shall operate efficiently over a long period of continued use.

The present wave motor includes means for compensating for the difference in speed 30 between incoming waves and outgoing waves, and means for balancing and steady- 35 ing the various parts in their operation to insure even flow of power from a driven shaft or shafts. These means comprise in one form a pair of driven shafts each of which has thereon a pair of clutches of unequal size driven from a drum actuated by a paddle by the to-and-fro movement of waves, the drum serving to drive cables extending to the clutches. The clutches prefer- 40 ably include sliding plates adapted to disengage freely on reverse movement without consuming any power whatever for disengagement. The two driven shafts with the drum constitute a unit and the shafts serve 45 to cooperate to render operation uniform and steady, a fly wheel being provided on one shaft if desired to assist in equalization, while certain of the cables may pass over idle pulleys which serve as shock absorbers 50 between the drum and the respective clutches, thereby further assisting even operation. Two such units preferably are coupled and are arranged to receive impulses 55 from waves at different times, also for the purpose of uniformity.

The invention resides further in the various combinations of parts and features of construction disclosed herein, pointed out in the appended claims, and illustrated in the accompanying drawings.

In the drawings wherein certain embodiments are shown by way of example,

Fig. 1 is a side elevation of one unit of the present invention;

Fig. 2 is a vertical section through that 65 clutch on the driven shaft at the left of Fig. 1 which is being driven from the drum by an incoming wave;

Fig. 3 is a like view showing the position 70 of a similarly operated clutch on the shaft at the right of Fig. 1;

Fig. 4 is a corresponding view of the other clutch on the left shaft showing the movement of the same while reversing under movement of the drum and paddle to drive 75 the clutches of Figs. 2 and 3;

Fig. 5 is a similar view of the second clutch on the right shaft;

Fig. 6 is a vertical transverse section 80 through the two clutches on the right shaft of Fig. 1 as indicated by the line 6-6;

Fig. 7 is an elevation showing diagrammatically the connection of two units of the present invention; and

Fig. 8 is a sectional detail through the 85 drum taken on the line 8-8 of Fig. 1.

The wave motor is shown as being carried upon piles 10 carrying supporting beams 12 provided with bearings 14 for the shaft 15 of the heads 16 of a cable carrying 90 and driving drum 18. Said heads 16 may be shouldered as seen in Fig. 8 for positioning said drum, and the parts are held by means of bolts 20. Depending arms 22 which support a paddle 24 extend within the drum 95 heads and are carried and positioned by means of the shaft 15 and a bolt 20, whereby the drum and its cables are actuated upon oscillation of the paddle. Drum 18 is provided with annular grooves 25 for the reception of a plurality of cables as shown in Fig. 8.

The cables are arranged in two pairs, a pair extending on each side of the drum, each cable passing around the drum and being secured thereto if necessary in any suitable manner. Of the right pair which serves to drive the primary or main drive shaft A of the unit, the cable 30 is crossed 105 while the cable 32 extends directly to and 110

from the drum. Of the left pair of cables which drive a secondary shaft B, the cable 34 is crossed while the cable 35 runs direct. Some or all of the cables are carried over 5 idle pulleys 36 mounted on supports 38, these pulleys serving as shock absorbers between the drums and the clutches 40, by controlling any slack in the cables and taking up any slack or back-lash, so that the 10 flow of power transmitted from the drum will be as constant and uniform as possible. This uniformity is promoted by employment of a fly wheel F on the main shaft A, or where a second unit is employed, as is preferred and as shown in Fig. 7, the fly wheel F may be carried on the main shaft A' of said second unit; or fly wheels may be used on two or more shafts as required.

20 A clutch is provided for actuation by each cable, the cables 30 and 34 passing over small pulleys 42 preferably formed integral with the housings 40' of the respective clutches, while the cables 32 and 35 are passed over large pulleys 44 formed on the 25 housings 40 of the respective clutches. The pulleys 44 are approximately three times the diameter of the pulleys 42 to compensate for the greater rate of speed of the incoming waves over the rate of the receding water, for the purpose of evening and rendering 30 nearly constant the flow of power to the shafts A and B and thence to devices to be driven.

35 The construction of the various clutches is identical except for the difference in size of the pulleys 42 and 44. However, a clutch housing having either pulley size may be machined from the same casting merely by cutting down to the required 40 diameter. Each housing 40 and 40' has a cover 48 secured thereto by means of screws 50, the covers being apertured at 52 and the housings being recessed at 53 to receive 45 pivoting stems or pins 54 of clutch blades 55 which are adapted to engage shoulders 56 of hubs 58 keyed at 60 on the respective shafts A and B. Screws 62 serve to hold the clutches against longitudinal movement 50 on the shafts.

55 It is preferred to employ a unit comprising the shafts A and B and associated members with a second unit comprising the shafts A' and B' and similar associated parts as indicated in Fig. 7, and for this purpose the primary shafts A and A' of the two units are provided with pulleys 64 (Fig. 6) for a connecting belt 65. These units will be so spaced along the path of incoming waves as to have the paddles actuated at different times, that is by waves at different stages of movement so that the 60 flow of power will be more even.

In operation oscillatory movement of the paddles will cause the drums 16, 18 to actu-

ate the clutches 40, 40' and thereby the 65 shafts A and B, and A' and B', through the various cables 30, 32, 34 and 35. When the paddles 24 are actuated by an incoming wave, as indicated, the cables 32 and 35 will cause the blades 55 of the respective clutches 70 40 to engage their shoulders 56 and to rotate the shafts (Figs. 2 and 3), while the blades 55 of the clutches 40' will be moved in the reverse direction by their crossed cables 30 and 34 and will ride freely over their shoulders 56. Upon actuation by the receding water, whose rate is slower, the clutches 40' will cause rotation of the shafts at substantially the same rate due to the smaller size of the pulleys 42. By providing the idle 75 pulleys 36 shock or slap of the cables is prevented and is not transmitted to the clutches. By provision of the two shafts A and B in each unit, the action of one sufficiently cooperates with the action of the other to equalize and steady the operation while the fly wheel F wherever used assists to insure uniform and constant flow of power. Shaft A may be used to drive a generator and shaft B may be connected for driving light machinery or the like. Where two units are used and the shafts A and A' are connected by belt 65 (Fig. 7), power for driving a generator may be taken from one of these shafts only, while power for auxiliary purposes may be taken from the shafts B and B' as desired.

Thus, it will be seen that we have provided a simple and efficient wave motor which may be operated continuously to yield a substantially constant and uniform flow of power to any driven device.

Also it will be seen that the use of two or more units will improve the uniformity of operation.

We claim:

1. A wave motor comprising an oscillating member, a pair of drive shafts driven thereby, a pair of clutches for driving each shaft, pulleys of different diameters connected with the clutches of each pair for driving the same, and cables connecting said member with said pulleys for driving both shafts continuously in the same direction.

2. A wave motor comprising an oscillating drum, a shaft having a pair of clutches thereon, each clutch having a cable receiving surface in the form of a pulley face, the clutch pulleys having different diameters and being adapted to drive the shaft in the same direction upon opposite movements of the drum, and cables extending from said drum to said pulleys.

In testimony whereof we affix our signatures.

JOHN J. MANN.
